DESIGN FOR AN ARTIFICIAL BOUTONNIERE

Adele G. Spilka, New York, N. Y.

Application March 15, 1943, Serial No. 109,754

Term of patent 3½ years

To all whom it may concern:

Be it known that I, Adele G. Spilka, a citizen of the United States and a resident of city, county, and State of New York, have invented a new, original, and ornamental Design for an Artificial Boutonniere, of which the following is a specification, reference being had to the accompanying drawing, forming part thereof.

Fig. 1 is a front elevational view of an artificial boutonniere showing my new design; and Fig. 2 is a side view thereof.

I claim:

The ornamental design for an artificial boutonniere, substantially as shown.

ADELE G. SPILKA.
